UNITED STATES PATENT OFFICE.

CLILE C. ALLEN, OF CHICAGO, ILLINOIS, ASSIGNOR, BY MESNE ASSIGNMENTS, TO NEW YORK LENS COMPANY, INC., OF NEW YORK, N. Y., A CORPORATION OF NEW YORK.

APPARATUS FOR GRINDING ONE-PIECE BIFOCAL LENSES.

1,261,674.

Specification of Letters Patent.

Patented Apr. 2, 1918.

Application filed May 11, 1914, Serial No. 837,935. Renewed January 8, 1917. Serial No. 141,339.

To all whom it may concern:

Be it known that I, CLILE C. ALLEN, a citizen of the United States, residing at Chicago, in the county of Cook and State 5 of Illinois, have invented certain new and useful Improvements in Apparatus for Grinding One-Piece Bifocal Lenses, of which the following is a specification.

The present invention has reference to 10 certain improvements in apparatus for grinding lenses, and particularly bi-focal lenses, in which the reading and distance fields are formed in the same one-piece lens crystal. The invention has reference more 15 particularly to an apparatus for grinding lenses of this type in which the surfaces of the reading and distance fields are concentrically ground.

In this class of work, it is very important 20 that the apparatus should be of such construction that the two fields may be so ground as to bring their line of joinder into a surface common to both fields, thereby avoiding any shoulder or step at the line 25 of joinder of the two fields. In order that this result may be obtained with nicety and certainty, the apparatus must be so constructed and operated that assurance may be had that the two fields are, in fact, concentrically ground—that is, ground in such 30 a way that the centers of the spheres, on which they are ground, lie on the same radial line. Unless this precaution be taken in the construction and operation of the apparatus, it will be found when the two fields 35 are completed that they are tilted or tipped with respect to each other, so that on one portion of the line of joinder there will be a shoulder facing the reading field, whereas 40 on another portion of the line of joinder there will be a shoulder facing the distance field.

In the past it has been the main aim of inventors working in this art to try and 45 produce an apparatus of such construction that the two fields can be concentrically ground at the same time or simultaneously. When the fields are to be simultaneously ground, the apparatus must be very nicely 50 and accurately constructed and operated in order to cause the crystal to rotate always with the center of its radius of generation at the same point in space. Unless the apparatus be thus constructed, the center of 55 the radius of generation will move around

as the crystal rotates, and consequently the crystal will wobble during its rotation. Inasmuch as the two grinding laps are simultaneously in operation, and are grinding the crystal on both sides of the center line simultaneously, and inasmuch as these laps are substantially stationary, it will be found that the two fields will be tilted in the objectionable manner above mentioned when the crystal is complete. 60

I have discovered that, if the two fields be individually ground, each lap may rise and fall periodically with the rotation of the crystal in order to compensate for the wobbling of the crystal, as it is found to be 65 practically impossible to always replace the crystal on the spindle head or holder in the same position with respect to the axis of rotation, so that the field which is being operated on will be perfectly ground concentrically with the radius of the circle on 70 which the crystal rotates, notwithstanding any slight wobbling motion. If then the other surface be afterward ground, the lap used in such second grinding operation will 75 likewise be able to continuously adjust itself during the rotation of the crystal, so that the surface of such second field will also be concentric with the axis on which the crystal rotates, and thus in the end both 80 fields will be correctly ground. In order, however, that this individual grinding process may be successfully practised, it is desirable, if not imperative, that the apparatus should be so constructed that the two 85 grinding operations may be properly controlled. This control includes a proper centering of the grinding laps with respect to the axis of crystal rotation, as well as a control of the eccentricity of movement or vibration of the laps, for the purpose of properly centering the laps with respect to the 90 center of crystal rotation during their oscillation or vibration. 95

The apparatus to which the present invention particularly relates is, therefore, so constituted or constructed that the desired several adjustments can be very nicely secured in order to enable the individual-field-grinding process to be successfully practised 100 for the production of an optically perfect bi-focal lens.

Other objects and uses will appear from a detailed description of the invention, which consists in the features of construc- 110

tion and combinations of parts hereinafter described and claimed.

In the drawings—

Figure 1 shows a side elevation of one form of apparatus for carrying into practice the features of the present invention;

Fig. 2 shows a plan view of the mechanism shown in Fig. 1;

Fig. 3 is a horizontal section through the 10 turn buckle;

Fig. 4 is a detailed vertical section through one of the lap pressure-pins;

Fig. 5 is a cross section through an unground crystal;

Fig. 6 is a cross section through the crystal after the completion of the reading field;

Fig. 7 is a cross section through the crystal after the completion of the distance field; and

Fig. 8 is an enlarged detail of a portion of the crystal of Fig. 7, showing how the grinding lap may be caused to provide a substantially perfect line of joinder between the two fields by carrying forward the grinding and 25 polishing operations individually instead of simultaneously.

Fig. 9 is a vertical section taken on line 9—9 of Fig. 2 looking in the direction of the arrows.

In Figs. 1 to 4, inclusive, I have shown one construction of mechanism which embodies the features of my invention, while in Figs. 5 to 8, inclusive, I have shown one series of steps or operations on the crystal by means 35 of which my individual field grinding process may be carried into effect.

In the construction shown in Figs. 1 to 4, inclusive, there is provided a crystal-carrying head 9 and an oscillatable head 10. The 40 head 9 is carried by a vertical spindle 11, which may be rotated rapidly in any desired manner. The head 10 carries two or more lap centering pins 12 by means of which the particular lap or laps in service 45 are held in operative engagement with the crystal. In the particular arrangement illustrated in the several figures there are two of these pins, a central one for the lap which grinds the reading field and a side 50 one for the lap which grinds the distance field. The laps may be of any one of a number of familiar forms, as, for example, that form in which the lap is provided on its upper surface with a lug having a slight depression or socket to receive the point of the 55 pin.

Assuming that the individual field grinding process is to be practised by grinding the reading field first, a lap having the desired curvature and of the desired size would be placed on the crystal (the crystal having first been secured to the head 9 in a usual manner), and then the grinding operation would be commenced and allowed to 60 continue until the reading field had been

ground down the desired amount, as shown at 13 in Fig. 6. After the reading field had thus been ground down, the reading grinding lap would be removed, and then the field 13 would be polished in any desired manner. 70 It would be found after these operations had been completed that there remained a small rounded portion 14 around the edge or periphery of the shoulder, as shown greatly exaggerated in Fig. 8. The grinding 75 of the distance field would then be commenced. In the apparatus illustrated there is provided but a single pin for applying pressure to a single distance grinding lap, and this is the preferred arrangement. 80 Having applied the distance grinding lap to the crystal, and having applied pressure thereto, the parts should be so adjusted that the distance grinding lap 15 would overlie or project beyond the edge of the 85 reading field, as previously ground, as is illustrated in exaggerated form in Fig. 8. The grinding of the distance field would then be proceeded with until this field had been ground down to such an extent that the 90 previously formed shoulder would be completely wiped out, and the two fields had been brought together on the same line of joinder. It is desirable under any circumstances to allow the distance grinding lap 95 to overlie the shoulder of the reading field a slight amount to insure a proper removal of crystal from the distance field clear up to the reading field. This overlap, however, is not objectionable for the reason that, as 100 the surface of the distance field approaches that of the reading field, the rounded or curved portion 14 of the shoulder will gradually be wiped out until finally a practically perfect line of joinder is secured between the 105 two fields. After the grinding of the distance field has been completed, this field may be polished in order to complete the fourth step in the process of producing the crystal having the two fields individually ground of 110 desired dioptrics. Thereafter the crystal may be cut into two parts for the production of a pair of lenses in the usual manner.

In case it be desired to grind the distance field first, this may be done, in which case 115 the lap used in grinding the reading field would afterward be chosen of such a size and would be manipulated in such a manner as will presently appear, to completely eliminate the shoulder between the fields so as to 120 produce a substantially perfect lens after the several grinding and polishing operations had been completed.

The head 10 is pivotally connected to a yoke 16 so that the head may be swung up 125 and back into the dotted line position 17, as shown in Fig. 1. The yoke 16 is supported on the upper end of a rock arm 18, which is pivoted to a stationary pivot 19, so that the yoke may rock with a straight back and 130

forth movement in order to carry the grinding lap which is in operation through the desired amount of back and forth movement. At the same time the arm 18 is broad enough, and its pivotal points 19 are sufficiently far apart, to prevent any sidewise or twisting movement of the head 10.

In the rear portion of the apparatus there is provided a vertical spindle 20, having 10 on its upper end a head 21. An eccentric plate 22 is pivoted to the head 21 at the point 23, its other end being provided with a slot to receive a pin or set screw 24. By means of this pin and slot connection the plate 22 15 may be locked in any desired position on the head 21. The plate 22 in turn carries a crank pin 23^a on which rides the collar 24^a. A yoke 25 is pivoted to the collar 24^a by means of the pins 26, so that said yoke will 20 be driven back and forth to a distance depending upon the amount of eccentricity created by the plate 22. The yoke 25 connects to the yoke 16 by means of a yoke 26^a and a turn buckle 27. This turn buckle is for the 25 purpose of adjusting the distance between the yokes 25 and 26^a, so that the extreme forward and backward limits of movement of the head 10 can be controlled. As a convenient construction of turn buckle, I have 30 shown the yokes 25 and 26^a as being provided with the lugs 27^a and 28, which are threaded to receive the ends of the turn buckle pin. These threads are formed in reverse directions, so that the mere turning of 35 the turn buckle pin will draw the yokes together or force them apart. I have shown the lugs 27^a and 28 as being split, and as carrying sleeves 29 provided with set-screws 30, so that the lugs 27^a and 28 can be clamped 40 onto the ends of the turn buckle pin after the desired adjustment has been secured, in order to prevent any disarrangement.

This turn buckle construction illustrates one means or construction for controlling 45 the forward and backward limits of throw of the head 10. Such a construction is desirable for the purpose of insuring an equal throw of the grinding laps to both sides of the center of rotation of the crystal. This 50 will insure an equal amount of grinding action on all portions of the crystal subjected to the action of the lap. The adjustable eccentric plate 22 permits the degree or extent of eccentricity to be regulated or varied. It 55 will be evident that the total diameter or size of the near or reading field will be equal to the diameter of the lap used in grinding it, plus the total amount of throw measured in a back and forth direction. Therefore, 60 the eccentricity adjustment permits adjustment of the diameter of this field when using a given size of lap, and in like manner permits the eccentricity to be adjusted according to the requirements or desirability 65 as determined by the particular lap which

is being used. It will, therefore, be seen that not only have I provided means for controlling the amount of eccentricity, but also have combined with this means for accurately adjusting the back and forth throw, 70 so that it will be equal on both sides of the center of rotation.

In Fig. 4 I have shown more in detail one form of pin for pressing a lap down into contact with the crystal. In the construction illustrated, the pin 12 is slidably mounted within a sleeve 31. The pin is provided with a channeled portion 32 adapted to receive a screw or pin 33 which will limit the downward movement of the pin 12. 75 The upper end of the pin 12 carries a stop or abutment 34, and a spring 35 exerts an expanding force tending to raise the pin 12 with respect to the sleeve 31. A screw cap 36 is threaded onto the upper end of the 80 sleeve 31, and limits the upward movement of the pin 12, so that the elevation of said pin can be accurately adjusted by means of this screw cap. The screw cap, if desired, may be provided with a scaled outer surface 37, whereby it may be set into different predetermined positions, thereby enabling the operator to bring the cap and the pin into any desired predetermined position. The sleeve 31 lies beneath 38 in Fig. 2. It 85 may be rigidly connected to the head 10, so that when said head is thrown into the horizontal position illustrated in Fig. 1 the weight of the head will be transmitted down through the pin and onto the grinding or 90 polishing lap. On the other hand, the sleeve 31 for the distance field lies beneath 39 in Fig. 2. This sleeve is preferably carried by an arm 40 pivoted to the head 10 at the point 41, and provided at its front end with 95 a slot 42 adapted to receive a set screw 43. The sleeve 31 itself projects down through a slot 44 of the head. It will thus appear that by rocking the arm 40 back and forth the pin 12 and the lap for grinding the distance field can be set the desired distance to one side of the center of rotation of the lens holder. In this way it is possible to very 100 nicely and accurately adjust the lap for grinding the distance field so as to secure 105 exactly the desired overlap such as is illustrated in Fig. 8, and for other purposes. 110 Assuming that the sleeves 36 stand in a given position, the head 10 will assume a definite angle when the proper pin 12 is 115 resting on the lap which is to be used. If the crystal be thick, or if the lap be thicker than usual, the head 10 will not set as far down as would otherwise be the case, and the head may assume an angle other than 120 at right angles to the axis of rotation of the head 10. It is desirable that the pins 12 should bear down exactly parallel to the 125 axis of rotation, both for the purpose of securing a more efficient and perfect pressure 130

on the lap and for the purpose of insuring an equal travel of the lap both sides of the center. The threaded heads 36 provide a simple means for setting the pins 12 up or down into the desired positions, so that the head 10 will assume a position at right angles to the axis of rotation.

The head 10 may be easily thrown or turned up into the position shown at 17 in Fig. 1, thereby permitting the operator to quickly release the pressure from the laps, and at the same time giving the operator full and perfect access to the crystal and laps at any instant during the grinding operation.

In Fig. 1 I have illustrated a convenient means for driving the spindles 11 and 20. The same includes a jack shaft 45 transmitting power through a belt 46 and to the loose and fast pulleys 47 and 48, respectively, which are mounted on the spindle 11. This spindle also carries another fast pulley 49 which drives backward through the medium of a belt 50 to the spindle 20. It thus follows that the act of shifting the belt 46 onto and off from the fast and loose pulleys simultaneously controls the rotation of both of the spindles.

I wish to point out that it is extremely desirable, in order to produce an optically perfect lens, to grind the fields separately and not simultaneously, and to allow the lap which is used in the second grinding operation to overlap the field which is first ground a slight distance so as to completely eliminate or wipe out the shoulder at the line of joinder between the fields.

While I have herein shown and described only a single form of apparatus embodying the features of my invention, still it will be apparent to those skilled in the art that many other arrangements or embodiments might be devised which would still be within the scope of my invention. Therefore, I do not limit myself to the arrangement illustrated and described except as I may do so in the claims, but I contemplate within the scope of my invention any equivalent mechanism operating in equivalent manners to produce equivalent results.

I claim:

1. In a lens grinding machine the combination with an upright spindle, and a crystal carrying head on its upper end, of another upright spindle, an eccentric pin on its upper end, means for adjusting the degree of eccentricity of said pin, a rock arm, a yoke pivotally connected to the upper end of the same, an adjustable connection between the eccentric pin and the yoke, an oscillatable head pivotally connected to the yoke, a centering pin carried by the yoke at a point centrally above the center portion of the crystal carrying head, means for adjusting the centering pin in and out with respect

to the oscillatable head to adjust the amount of extension of the centering pin therefrom, there being a slot in the oscillatable head, an arm swingingly mounted on the oscillatable head, a centering pin carried thereby, said centering pin extending through the slot aforesaid, means for locking the swinging arm in any desired position, and means for adjusting said centering pin in and out with respect to the oscillatable head to thereby adjust the amount of projection of said centering pin with respect to the oscillatable head.

2. In a lens grinding machine the combination with a spindle having on its upper end a crystal carrying head, of another spindle, an eccentric pin connected to the upper end of said last named spindle, means for adjusting the degree of eccentricity of said eccentric pin with respect to its spindle, a rock arm swingingly connected to a stationary part, an oscillatable head pivotally connected to the upper end of said rock arm, a driving connection from the upper end of the rock arm to the eccentric pin, means for adjusting the length of said driving connection, a centering pin connected to the oscillatable head at a point centrally above the crystal carrying head, means for adjusting said centering pin in and out with respect to the oscillatable head to thereby adjust the amount of extension of said centering pin beyond the oscillatable head, there being a slot in the oscillatable head, an arm pivotally connected to the oscillatable head, a centering pin carried by said arm and extending through the slot, and means for adjusting the amount of projection of said centering pin beyond the oscillatable head.

3. In a lens grinding apparatus the combination with a rotatable spindle having on its upper end a crystal carrying head, of another spindle, an eccentric pin carried thereby, means for adjusting the amount of eccentricity of said pin, a rock arm swingingly connected to a stationary part, an oscillatable head pivotally connected to the upper end of said rock arm, an adjustable connection between the upper end of the rock arm and the eccentric pin, a centering pin carried by the oscillatable head centrally above the crystal carrying head, another centering pin connected to the oscillatable head at a point to one side of the first mentioned centering pin, both of said centering pins projecting beyond a surface of the oscillatable head and toward the crystal carrying head, and means for adjusting the extent of such projection of each centering pin.

4. In a lens grinding apparatus the combination with a rotatable spindle having a crystal carrying head on its upper end, of another spindle, an eccentric pin connected to its upper end, a rock arm swingingly connected to a stationary part, a connection be-

tween the upper end of said rock arm and the eccentric pin, means for accurately adjusting the length of said connection, an oscillatable head pivotally connected to the
5 upper end of the rock arm, a centering pin carried by the oscillatable head centrally above the crystal carrying head, another centering pin carried by the oscillatable head at one side of the first mentioned centering pin, both of said centering pins extending beyond the lower surface of the oscillatable head, and means for individually adjusting the amount of such extension of each centering pin.

15 5. In a lens grinding apparatus the combination with a rotatable spindle having a crystal carrying head, of another spindle, an eccentric pin connected thereto, a rock arm swingingly connected to a stationary part, a connection from the upper end of the rock arm to the eccentric pin, means for accurately adjusting the length of said connection, an oscillatable head pivotally connected to the upper end of the rock arm, a centering pin carried by the oscillatable head centrally above the crystal carrying head, another centering pin carried by the oscillatable head above the crystal carrying head and to one side of the first mentioned centering pin, both of said centering pins projecting beyond the lower surface of the oscillatable head, and means for individually adjusting the amount of such extension of each centering pin.

35 6. In a lens grinding apparatus the combination with a rotatable spindle having a crystal carrying head connected thereto, of another spindle, an eccentric pin connected thereto, an oscillatable head pivotally connected to a reciprocable part, and a connection from the reciprocable part to the eccentric pin, means for accurately adjusting the length of said connection, a centering pin carried by the oscillatable head centrally above the crystal carrying head, another centering pin carried by the oscillatable head above the crystal carrying head and to one side of the first mentioned centering pin, both of said centering pins extending below the surface of the oscillatable head, and means for individually adjusting the amount of such extension of each centering pin.

7. In a lens grinding apparatus the combination with a rotatable spindle having a crystal carrying head connected thereto of another spindle, an eccentric pin connected thereto, a reciprocable part, a connection between the reciprocable part and the eccentric pin.

tric pin, means for accurately adjusting the length of said connection, means for adjusting the degree of eccentricity of the eccentric pin, an oscillatable head pivotally connected to the reciprocable part, a centering pin carried by the oscillatable head centrally above the crystal carrying head, another centering pin carried by the oscillatable head above the crystal carrying head and to one side of the first mentioned centering pin, both of said centering pins projecting below the lower surface of the oscillatable head, and means for individually adjusting the amount of such extension of each centering pin.

8. In a lens grinding apparatus the combination with a rotatable spindle having a crystal carrying head, of another spindle, an eccentric member connected thereto, a reciprocable member, a connection from the eccentric member to the reciprocable member, an oscillatable head pivotally connected to the reciprocable member, a centering pin carried by the oscillatable head at a point centrally above the crystal carrying head, another centering pin carried by the oscillatable head above the crystal carrying head and to one side of the first mentioned centering pin, both of said centering pins projecting beyond the lower surface of the oscillatable head, and means for individually adjusting the amount of such extension of each centering pin. 75 80 85 90

9. In a lens grinding apparatus the combination with a rotatable spindle having a crystal carrying head connected thereto, of another spindle, an eccentric member connected thereto, a reciprocable member, a connection from the reciprocable member to the eccentric member, means for accurately adjusting the length of said connection, an oscillatable head pivotally connected to the reciprocable member, means for adjusting the amount of eccentricity of the eccentric member, a centering pin carried by the oscillatable head centrally above the crystal carrying head, another centering pin carried by the oscillatable head above the crystal carrying head and to one side of the first mentioned centering pin, both of said centering pins extending beyond the oscillatable head and toward the crystal carrying head, and means for individually adjusting the amount of such extension of each centering pin. 95 100 105 110
